UNITED STATES PATENT OFFICE

AUGIE L. HANSEN, OF CHICAGO, ILLINOIS, ASSIGNOR TO A. L. HANSEN MFG. COMPANY,
OF CHICAGO, ILLINOIS, A CORPORATION OF ILLINOIS

DISPLAY STAND

Application filed October 7, 1929. Serial No. 397,820.

This invention relates to improvements in display stands especially adapted for the counter display and sale of confections, chewing gum, and the like.

5 The object of the invention is to provide a simple and inexpensive type of display stand which can be distributed in a convenient collapsed or knocked-down form, can be readily set up by the retailer for the display of goods, and when set up and filled with boxes of the confection will afford an attractive display.

In the distribution of packaged confections, such as chewing gum, hard candies, mints, and the like, it is not uncommon for the manufacturer to supply the retailer through jobbers or other distributing agencies with a display stand or rack, either free of charge or at a small cost which is included in the cost of the goods. For instance, a display stand may be included in each shipment of a certain number of boxes or cartons, so that the retailer is not only provided with a convenient means for displaying the goods on his counter, but the manufacturer is assured that his goods will be attractively and with uniformity displayed to the public. Of necessity, therefore, the stands should be inexpensive, capable of being shipped in a compact knocked-down form so that they can be shipped in the same carton with the goods or separately, if need be, at the lower rates of postage or transportation, and finally to be of a substantial as well as inexpensive construction.

35 A preferred embodiment of the invention is disclosed in the accompanying drawings, in which

Figure 1 is a perspective view of the stand in position for use; and

Figure 2 is a view of the stand collapsed for shipment.

In general, the stand comprises three pivotally connected sheet metal plates or members, one providing a base 1, another forming an inclined easel-like support 2, and the third, a brace or leg 3 for the inclined support. The base 1 and inclined support 2 are substantially of the same dimensions, being rectangular in shape and somewhat

greater in length than in width. Considering first the base 1, the marginal portions are bent upwardly at right angles to provide flanges 1a, 1a and 1b, 1b along the sides and ends, respectively, the corners of the plate being preferably cut away on the diagonal before the flanges are formed so as to leave blunt corner edges and spaces between the inclined ends of the flanges. The flanges are all of the same height except one of the end flanges 1b, which is disposed at the rear when the stand is set up.

The supporting plate 2 is similar in all respects to the base 1 with the exception of the omission of an end flange along its lower edge where it is hinged to the base plate midway between the ends thereof and the presence of a short flange 2a along its upper or free edge which is bent rearwardly instead of forwardly as are the side flanges 2b, 2b. The supporting plate is connected to the base plate by pivot pins 4 inserted through the side flanges 1a of the base plate and the lower ends of the side flanges 2b of the supporting plate, the latter lying inside the former.

The third member of the assembled parts, hereinbefore referred to as the brace or leg 3, is a plate about one-half the length of the supporting plate 2 and is pivotally connected thereto a short distance beyond its mid point and toward its free edge. This plate is flanged along its side edges and its free edge. The side flanges 3a, 3a are tapered from the inner toward the outer edges of the plate, their inner extremities projecting beyond the adjacent edge to form rounded ears embracing the side of the supporting plate and through which pivot pins 5, 5 are inserted. By this arrangement, the brace plate is capable of being swung away from the supporting plate but its movement is limited by contact of its hinged edge with the face of the supporting plate to the angle which will give the latter the proper inclination when the stand is set up.

As shown in Figure 1, the supporting plate assumes a rearwardly inclined position or slope when the stand is set up for use, being firmly braced by the leg 3 which

is held at its lower edge by the flange 1b along the rear edge of the base plate. It may be observed that the free edge of the leg 3 is flanged as at 3b primarily to avoid 5 a sharp edge, the same being true of the flanged upper edge of the supporting plate 2.

As the stand is proportioned it is capable of supporting three boxes, A, B, and C, of confections which are indicated in dotted 10 lines in Figure 1. Thus one box A fits within the shallow recess formed by the forward half of the base plate, a second box B against the inclined supporting plate and resting on the rear edge of 15 the horizontal box, and the third box C above the second, projecting a short distance above the upper edge of the supporting plate. All of the boxes are thus confined against shifting by the flanged side 20 edges of the plates against which they rest, and yet can be readily removed to permit fresh boxes of confections to be inserted as required.

Figure 2 shows the stand in collapsed position for shipment in which the brace plate 25 3 is merely swung inwardly against the supporting plate, and the supporting plate swung forwardly and downwardly onto the base plate. While the supporting plate is 30 free to swing in either direction relative to the base plate, it is preferable to swing it forwardly and downwardly from the set up position, since the brace plate is thus disposed outermost rather than between the 35 base and supporting plates, which makes a somewhat flatter package. The length, however, would be the same in either case, since the supporting plate would project the same distance beyond either end of the base plate. 40 In other words, the collapsed stand is one and one-half the length of the base plate, and its thickness is slightly greater than the width of the side flanges, which telescope when the plates are folded together. If 45 desired, an opening 6 may be cut or punched in the supporting plate opposite the brace plate for convenience in pushing the same outwardly when the stand is being set up.

Having set forth the structure and manner 50 of use of the stand embodying my invention,

I claim:

1. A collapsible display stand comprising a base plate having side and end flanges, a 55 supporting plate hinged along one edge to said base plate intermediate the ends thereof and a brace member hinged to said supporting plate intermediate its ends, said supporting plate being normally braced in an inclined position with the free edge of 60 said brace member abutting the adjacent flanged edge of said base plate to provide horizontal and rearwardly inclined tray sections.

2. A collapsible display stand comprising 65 a base plate having upstanding side and end

flanges, a supporting plate having hinged connection at one end to the side flanges of said base plate substantially midway the ends thereof, and provided with side flanges and a brace plate hinged along one edge to 70 said supporting plate substantially midway of its ends, and normally adapted to brace the same in an inclined position with the free edge thereof abutting the adjacent flanged end of said base plate, said supporting plate and the portion of the base plate on the opposite side of said supporting plate from said brace, forming flanged box-retaining trays arranged at an obtuse angle 75 to each other.

Signed at Chicago, Ill., this 3rd day of October, 1929.

AUGIE L. HANSEN.
